ART OF PACKAGING

Milton Bennett, Briarcliff Manor, N. Y., assignor
to Milprint, Inc., Milwaukee, Wis., a corporation
of Delaware

Application October 29, 1942, Serial No. 463,795

2 Claims. (Cl. 93—36.01)

This invention relates to improvements in the art of packing batches of diverse commodities for handling and merchandising purposes, and relates more especially to improvements in the construction of composite wrappers and to an improved method of producing such composite wrapper assemblages and of packing materials therein.

An object of the present invention is to provide a new and useful composite wrapper for batches of diverse commodities, and an improved method of effectively producing the wrappers.

It has previously been proposed to provide various styles of composite wrappers each consisting of an outer relatively rigid box or carton lined with a thinner and more flexible sheet of material of bag-like formation, for the purpose of packing batches of diverse commodities, and such composite wrapping assemblages have gone into quite extensive use. Considerable difficulty has heretofore been encountered in causing the highly flexible sheets or liner bags to hug all portions of the interiors of the stiffer outer cartons, and also in properly maintaining the liners in proper place after initial positioning thereof within the boxes. In many of the prior lined boxes, the relatively thin linings are not sufficiently protected while permitting convenient access to the interior of the wrappers for inspection and display purposes; and most of the previous structures of this general type cannot be quickly and conveniently manufactured and assembled without the aid of complex and costly machinery.

The present invention therefore contemplates the provision of an improved method whereby relatively rigid boxes or cartons may be quickly and effectively lined with snug-fitting flexible liner bags, in such manner that the liners are permanently maintained within the cartons and the interiors of the lined boxes are conveniently accessible at all times.

Another specific object of my present invention is to provide an improved composite wrapper assemblage of the type comprising an outer relatively stiff shell and an inner flexible lining in the form of a bag.

A further specific object of this invention is to provide an improved method of effecting concealment of batches of commodity within composite wrappers in such manner that the commodity will be thoroughly protected but still readily accessible for inspection and display.

An additional specific object of the invention is to provide an improved lined carton assemblage

in which the enclosed commodity can be periodically removed in small doses and resealed after each withdrawal of a dose.

Still another specific object of my invention is to provide an improved mode of applying and of attaching a flexible bag liner within a prismatic outer carton or the like, so that the lined carton may be readily loaded and effectively sealed.

Another specific object of this invention is to provide an improved duo-ply wrapper assembly which is simple, compact and durable in construction, and which can be readily constructed at moderate cost and with simple equipment.

These and other objects and advantages of the present improvement will be apparent from the following description.

A clear conception of the several steps constituting my improved method, and of the construction of the improved composite wrapper resulting from the use of the method, may be had by referring to the drawing accompanying and forming a part of this specification wherein like reference characters designate the same or similar parts in the various views.

Fig. 1 is a somewhat diagrammatic part sectional perspective view illustrating the initial or first step of my improved method of producing bag lined cartons, with the aid of simple equipment;

Fig. 2 is a similarly diagrammatic and part sectional side view showing the start of the second step;

Fig. 3 is a view similar to that of Fig. 2 showing a continuation of the second step of the improved method;

Fig. 4 is another similar view showing the completion of the second step of the method;

Fig. 5 is a part sectional side view of one of the bag lined cartons filled with commodity and being subjected to the third or initial closure step of the improved method of packaging;

Fig. 6 is a part sectional perspective view illustrating a continuation of the third or closure step; and

Fig. 7 is a part sectional side elevation of the final package, showing the closure flaps of the outer or closure carton in open position.

Although the invention has been shown and described herein as being applied to a method of forming composite wrappers each comprising a rigid rectangular prismatic main carton lined with a highly flexible transparent bag and closed or sealed by means of a transparent cover sheet and a rigid rectangular prismatic cover carton coacting therewith, it is not intended to thereby un-

necessarily restrict the scope or utility of the method which may also be applied to the production of wrappers of other shapes and sizes not necessarily utilizing the closing or sealing means disclosed herein.

Referring to the drawing which depicts the several steps of the improved method, it should be understood that while this method may be carried on by hand, commercial exploitation thereof is facilitated by utilizing relatively simple apparatus such as a rigid form 9 having a base 10; a hollow rectangular or tubular wall 11 extending upwardly from the base 10 and being provided with opposite air-escape or vent grooves 12; and a rectangular folding frame 13 surrounding and spaced from the lower portion of the wall 11 and being supported from the base 10 by means of extensions 14, see Figs. 1 to 4 inclusive. This form 9 may be constructed of sheet metal or other suitable material and should be of such size and shape that it will approximately fit and properly cooperate with boxes or cartons of the particular size and shape which are to be lined thereon.

Each of the completed composite wrappers which are adapted to be manufactured or assembled with the form 9 by my improved method, comprises a main box or relatively rigid carton 15, a flexible sheet liner or lining bag 16, a transparent flexible closure sheet 17, and a cover or closure box or rigid carton 18 of such size and shape that it may be slipped over the remainder of the wrapper assemblage. All of these elements have been shown more or less diagrammatically and thicker than they actually are in practice, in order to clarify the disclosure.

The rigid main and closure cartons 15, 18 may be formed of cardboard or other suitable relatively stiff sheet material, and the bottom of the main carton 15 may normally be closed in any suitable manner as by flaps 19, while the top of the cover carton 18 is preferably provided with readily openable flaps 20 as shown in Figs. 6 and 7. The main rigid carton 15 of each wrapper, may also be provided with an adhesive outer band or area 21 near the open end thereof as indicated in Figs. 2, 3, 5 and 6, and both cartons 15, 18 are adapted to be folded flatwise or collapsed when their flaps 19, 20 are opened or distended.

The liners 16 which are preferably of bag-like formation, may be formed of relatively tenacious but thin and highly flexible sheet material such as regenerated cellulose film or rubber compound sheeting. These bag liners 16 may be transparent, opaque, or semi-transparent, and preferably have box-like bottoms 22 and are adapted to be collapsed so that they may be stacked compactly. The flexible closure sheets 17 may be formed of similar sheet material, but are preferably relatively transparent in order to permit inspection and display of commodity 23 which may be confined within the wrapper assemblages, when the flaps 20 of the closure carton 18 are opened as in Fig. 7. The liner bags 16 should be of such size and shape that they may be rather snugly positioned over the form 9 when the bags are distended, and the sheets 17 should be considerably larger than the carton openings which they ultimately cover and close.

In carrying on the present improved method of assembling the wrappers and of packing batches of the commodity 23, each liner bag 16 should first be distended, inverted and posi-

tioned over the form 9 with the mouth portion of the bag embracing the lower frame 13, as illustrated in Fig. 1. An inverted cup-shaped main carton 15 should thereafter be lowered over the bottom 22 of the initially positioned bag 16 as shown in Fig. 2, and the carton 15 should subsequently be lowered to the position indicated in Fig. 3 wherein the open end of the rigid carton is about to enter the space between the frame 13 and the walls 11. The downward movement of the stiff main carton 15 should then be continued, and will cause the mouth portion 24 of the liner bag 16 to be folded snugly around the exterior of the carton 15 over the adhesive area 21, while at the same time stretching the bag liner 16 into snug engagement with the interior of the carton 15 and forcing the peripheral portion of the bag bottom 22 into the corners at the bottom of the main carton, as depicted in Fig. 4. During this lowering of the main carton 15 over the inverted bag 16 the air which is confined within the liner by the walls 11 of the form 9, will be slightly compressed and will thus assist the form in expanding the lining bag into snug engagement with the carton interior, but this compressed air eventually escapes through the grooves or recesses 12 of the form 9. When the carton 15 is finally lowered to its lowermost position, the upper end of the form 9 will force the periphery of the bag bottom 22 into snug contact with the bottom corners of the carton, and the frame 13 will likewise force the folded mouth portion 24 of the bag into snug engagement with the exterior of the carton 15 where the fold will be retained by the adhesive. The successive main cartons 15 may thus be quickly and effectively snugly lined with bag liners 16 permanently attached thereto, and may be freely removed from the form 9 after the lining has been applied.

The bag lined cartons 15 may subsequently be righted and loaded with commodity 23 as indicated in Fig. 5, and a transparent cover sheet 17 may then be placed centrally across the carton opening after which the peripheral or edge portions 25 of this sheet 17 should be bent downwardly over the outer fold 24 of the liner 16 as shown. An outer cover carton 18 may thereafter be slipped downwardly over the sheet portions 25 and main carton 15 as illustrated in Fig. 6, thereby completely concealing and thoroughly protecting the inner wrapper and the commodity 23. The commodity 23 may thereafter be inspected or displayed to prospective purchasers without permitting direct access thereto; but any desired portion of the material may be readily removed by merely withdrawing the closure carton 18 and removing the cover sheet 17, and the package can obviously be repeatedly reclosed to conceal and preserve the residual commodity.

From the foregoing detailed description it should be apparent that the present invention provides an extremely useful and effective composite wrapper assemblage for batches of diverse commodities, and an improved method of quickly and effectively producing the wrappers so as to conceal and protect the goods. The durable but flexible liner bags 16 are snugly applied to all of the internal surfaces of the rigid main cartons 15 and are maintained in proper position by the folded mouth portions 24 coacting with the exterior of the cartons 15, and while the use of adhesive at the areas 21 is not necessary, it aids in retaining the composite wrapper properly assembled. The reverse folding of the mouth

portion 24 of each liner, also clears the carton opening from obstruction and facilitates loading, and the use of the cover sheets 17 and closure cartons 18 finally protects the enwrapped commodity 23 while permitting convenient access thereto. The use of the simple form 9 also facilitates commercial exploitation of the improved wrapping method, and the pneumatic pressure created by the use of this form 9 co-operates with the form structure to insure snug application of the liners to the cartons without undesirable wrinkling of the thin and flexible bags. The improved composite wrappers may be produced in various sizes and shapes, and at moderate cost, and the method has proven highly satisfactory in actual use.

It should be understood that it is not desired to limit this invention to the exact steps of the method or to the precise construction of the equipment and packages, herein shown and described, for various modifications within the scope of the appended claims may occur to persons skilled in the art.

I claim:

1. The method of producing a composite wrapper, which comprises, loosely inserting the major portion of a flexible bag within a relatively rigid carton so that the mouth portion of the bag projects outwardly beyond the carton end opening, confining atmospheric air within the bag while 30

applying the carton thereto, and thereafter restrictively releasing confined air from within said bag so as to compress the said air and to cause the same to distend the bag into intimate contact with the carton sides and bottom while simultaneously positively forcing the peripheral bottom portions of the bag into snug engagement with the corners of the carton bottom and folding the projecting bag mouth portion over and into snug contact with the exterior of the carton around its open end.

2. The method of producing a composite wrapper, which comprises, loosely inserting the major portion of a flexible bag within a relatively rigid carton having an external adhesive area near its open end so that the mouth portion of the bag projects outwardly beyond said carton end, confining atmospheric air within the bag while applying the carton thereto, and thereafter restrictively releasing confined air from within said bag so as to compress the said air and to cause the same to distend the bag into intimate contact with the carton sides and bottom while simultaneously positively forcing the peripheral bottom portions of the bag into snug engagement with the corners of the carton bottom and folding the projecting bag mouth portion over and into intimate contact with said external adhesive carton area.

MILTON BENNETT.
